UNITED STATES PATENT OFFICE.

ISAAC SNOW, OF LAWRENCE, MASSACHUSETTS, ASSIGNOR TO DRAPER COMPANY, OF HOPEDALE, MASSACHUSETTS, A CORPORATION OF MAINE.

LOCM.

1,132,223.

Specification of Letters Patent. Patented Mar. 16, 1915.

Application filed April 4, 1914. Serial No. 829,675.

To all whom it may concern:

Be it known that I, ISAAC SNOW, a citizen of the United States, residing at Lawrence, county of Essex, and State of Massachusetts, have invented an Improvement in Looms, of which the following description, in connection with the accompanying drawings, is a specification, like letters on the drawings representing like parts.

- 10 The invention to be hereinafter described relates to looms for weaving, wherein the warp threads are separated to form a shed for the passage of a shuttle carrying the weft or filling threads.
- 15 Those skilled in the art are familiar with the difficulty experienced in forming smooth and even selvages to the cloth, especially when certain kinds or character of threads are employed, due to the fact that as the 20 shuttle is "picked" the weft or filling thread between the "fell" of the cloth and the shuttle first becomes slack and then drags over the warp threads as the shuttle proceeds to the opposite box. This slack enables the 25 weft or filling to assume a loop form and the twist already in the thread at once acts to turn the runs or parts of the loop about each other into a twisted loop. This may happen as the shuttle leaves the box, and then, 30 as the shuttle proceeds through the shed, it will pull upon this twisted loop and drag the weft or filling over the warp threads. The friction between the warp threads and the weft or filling, however, is such that movement of the weft or filling in response to the 35 shuttle pull fails to untwist or straighten out the parts of the loop but rather emphasizes this objectionable condition with the result that weft or filling is pulled from the 40 shuttle and the twisted loop of filling ultimately appears at the selvage of the cloth as a kink or snarl of thread. This is particularly liable to happen in the use of some kinds of thread, such for instance, as hard 45 twisted thread or where the thread is not sufficiently "set," and in any case these snarls or loops produce an uneven and objectionably rough selvage.

With these general conditions in mind, 50 the aims and purposes of the present invention are to provide means whereby a uniform, smooth, and even selvage will be formed in the cloth, all of which will best be made clear from the following description and accompanying drawings of one

form of such means for carrying the invention into practical effect, it being understood that the invention is not limited to the details of such means, but that it may be varied within the true scope of the invention as 60 defined by the claims.

In the drawings:—Figure 1 represents in plan view so much of one side of a loom as is necessary to show the present invention and the parts with which it coöperates. Fig. 2 65 is a similar view with the lay back of its front position and just prior to picking the shuttle; Fig. 3 shows a somewhat similar view just after the shuttle has been picked; Fig. 4 is a sectional detail on the line 4—4, 70 Fig. 2; Fig. 5 is a detached view of the filling loop preventer in one of its preferred forms.

In the drawings, the loom frame 1, the breast beam 2, the lay 3, the shuttle box 4, 75 shuttle 5, picker 6, picker stick 7, temple 8 and its holder, and the means for operating the lay and picker stick, as well as other general features of the loom, may be of any desired form or construction, and being well 80 understood by those skilled in the art, these parts and their operative relations need not be further shown or described herein. As shown, the loom is of the general type known as a filling replenishing loom and in which 85 the stand 9 for the hopper or feeder is shown as broken away, but it is to be distinctly understood that so far as the present invention is concerned, it is applicable to any usual form of loom, regardless of whether it be of 90 the filling replenishing type or not.

As hereinbefore noted, when the shuttle is in its box and the lay has beaten up the weft or filling thread, substantially as indicated in Fig. 1, the filling *c* extends from the edge 95 of the cloth *a* to the delivery eye of the shuttle, such portion of the filling of course being beyond the edge of the cloth. When the shuttle is picked this portion *c* of the weft or filling slackens as the shuttle moves from 100 its box into the shed. At this time the weft or filling is liable to become kinked or snarled, due to the twist in the weft or filling itself, and this kinked or snarled condition is liable to be increased by the frictional 105 drag of the filling over the warp threads *b* as the shuttle passes to the opposite box. When the filling becomes thus snarled or kinked, particularly if the snarl or kink depends below the warps in the lower shed 110

or has been thrown above the warps in the upper shed, this frictional drag becomes so great that instead of the weft or filling being straightened out between the edge of the cloth and the shuttle when the latter reaches the opposite box, the weft or filling will be drawn from the shuttle itself, leaving the snarl, kink or twist in the weft or filling beyond the edge of the cloth, thereby producing rough, uneven and objectionable selvage.

The present invention contemplates means for preventing the formation of such uneven or rough selvages, and as one form of such means provides a device on the front 15 of the lay between the warp threads and the adjacent shuttle box which may engage the weft or filling thread when the shuttle is in the adjacent box, and prevent the formation of snarls or kinks in the thread as 20 the shuttle proceeds to the box at the opposite side of the loom, all of which will presently appear.

Inasmuch as the device referred to prevents the formation of loops or snarls in 25 the weft or filling thread, it may, for identification merely, be hereinafter referred to as a filling snarl preventer, and as one form of such device it may comprise a hook secured to the front of the lay between the 30 shuttle box and the warp threads and having its open end facing to the rear.

In the drawings the snarl preventer is shown as a hook, 10, the lower end of which 35 may be secured to the front of the lay 3 by any suitable means such as a bolt 11. This hook is preferably bent forwardly at 12 to form a shoulder, as indicated, and then rises above the race 13, see Fig. 4, and has a downturned end 14 forming an entrance to 40 the snarl preventer facing to the rear of the loom, sufficient space being left between the snarl preventer and the reed 15, Fig. 4, to permit the shuttle 5 to freely pass as it is picked, from one box to the other.

From the construction thus far described, 45 it will be apparent that when the shuttle is in the adjacent box, the snarl preventer at that side of the lay will have presented to it the run of filling *c* between the fell of the 50 cloth and the shuttle. The filling extending through the shed at the fell of the cloth is at this time bound in to the cloth, so that as the lay moves back substantially as indicated in Fig. 2, the portion of the filling *c* passes into the control of the snarl preventer, as indicated in Fig. 2. When the shuttle 55 is thereafter picked, as indicated in Fig. 3, the snarl preventer still maintains its control of the filling extending from the 60 edge of the cloth, and as the shuttle proceeds to the opposite box, the filling, now under control of the snarl preventer, is drawn therefrom out of the open rear portion thereof, the filling dragging with substantially little or no friction over the hard

or metal surface of the snarl preventer. By reason of this substantially frictionless condition between the filling and snarl preventer, such pull upon the filling as the shuttle proceeds to and reaches the opposite box, 70 may be exerted upon the filling to straighten it and to eliminate therefrom any twist or snarl that would otherwise remain therein or be emphasized by the drag and friction between the filling and the warp threads. 75 In other words, the snarl preventer engages the filling between the edge of the cloth and the shuttle in the adjacent box, holds it as the shuttle is picked, and then permits such filling to be freely drawn 80 from the snarl preventer by the shuttle and straightened out, so that the portion of the filling between the previous and last picks will be straight and devoid of kinks or snarls. 85

It will be noted from Fig. 4 that the snarl preventer is not only positioned in front of the lay, but extends forward some distance and provides a support for the slack filling as the shuttle is picked from the adjacent 90 box.

In order that the filling may be readily withdrawn from the snarl preventer by the shuttle, the end portion 14 which forms the hook of the preventer is provided with inclined side portions 16. It may sometimes be desirable to insure that the filling shall not escape from the snarl preventer as the shuttle is picked and slack thread formed between the edge of the cloth and the shuttle, as indicated in Fig. 3, and to this end the snarl preventer may be provided with a safety tongue 17, preferably extending upwardly and toward the hook 14, the two parts 17 and 14 providing a passageway 18 100 for the filling between them. This tongue 17, like the hook 14, is preferably provided with inclined side portions 19, so that as the filling is drawn taut by the shuttle, the filling held by the snarl preventer may 110 readily escape through the passageway 18. It may be desirable to secure the snarl preventer adjustably to the lay and as one means to this end the snarl preventer and its tongue 17 may be formed with a slot 20 to 115 be engaged by the securing means 11, whereby upon slackening the securing means or the bolt 11, the snarl preventer may be adjusted into the desired position.

The snarl preventer may take various 120 forms, as will be evident from the character of the function accomplished thereby, but the hook device, as indicated in Fig. 4, has been found to be a good practical embodiment of this feature of the invention, the 125 two parts 14 and 17 preferably being bent forwardly as indicated, so that when the shuttle is in the adjacent box and the lay moves back as indicated in Fig. 2, the filling *c* between the cloth and the shuttle may 130

readily pass into the control of the snarl preventer. After the snarl preventer has taken control of the filling, as indicated in Fig. 2, the filling *c* cannot readily escape therefrom until, when the shuttle is picked, it draws the loop of thread about the inclined side portions of the hook 14 or tongue 17, as the case may be, whereupon the filling will readily escape with substantially 10 frictionless retardation by the smooth metal surface of these portions of the snarl preventer.

While the invention has been described in connection with the particular form of hook as constituting the snarl preventer, it will be at once obvious to those skilled in the art that various changes may suggest themselves, within the true scope of the actual invention, which is defined by the 20 claims.

What is claimed is:—

1. In a loom, the combination of the lay and shuttle boxes, and means to engage the filling between the cloth and shuttle box 25 and hold the loop formed in the filling as the shuttle is picked until the slack filling between the shuttle and cloth is taken up and then to give up said loop as the shuttle traverses the lay and pulls upon the filling 30 to prevent snarling or kinking of the filling at the cloth selvage.

2. In a loom, the combination of the lay and shuttle boxes, and a snarl preventer mounted on the lay and extending in front 35 of the race between the cloth and shuttle box to engage the filling within the loop formed in the filling as the shuttle is picked and then give up said loop as the shuttle traverses the lay and pulls upon the filling 40 to prevent snarling or kinking of the filling at the cloth selvage.

3. In a loom, the combination of the lay and shuttle boxes, a device movable with the lay to engage the service filling between 45 the cloth and shuttle box and extend within and hold the loop formed as the shuttle is picked and give up the loop under the pull of the shuttle when the slack in the filling between the cloth and shuttle has been taken 50 up to prevent snarls or kinks being formed in said loop.

4. In a loom, the combination of the lay and shuttle boxes, a hook having its open-

ing facing rearwardly and extending in front of the lay to engage the filling between 55 the cloth and shuttle box as the lay moves back and prevent snarling of the filling at the cloth selvage.

5. In a loom, the combination of the lay and shuttle boxes, a hook mounted on the 60 lay and extending in front of the race-way between the cloth and a shuttle box to engage the loop of filling formed as the shuttle is picked and give up that loop as the shuttle 65 pulls upon the filling.

6. In a loom, the combination of the lay and shuttle boxes, means to engage the filling between the cloth and shuttle-box and about which the filling is passed to form an inclosing loop therein as the shuttle is 70 picked and then give up that loop responsive to the pull of the shuttle to prevent the formation of an uneven selvage.

7. In a loom, the combination of the lay and shuttle boxes, a hook mounted on the 75 lay and projecting in front thereof to engage the filling between the cloth and shuttle box as the lay moves back, and a means to prevent the escape of filling from the hook until the shuttle pulls upon the filling. 80

8. In a loom, the combination of the lay and shuttle boxes, a hook mounted on the lay between the cloth and shuttle box and having its opening facing rearwardly to permit the engagement of the filling with 85 the hook as the lay moves back, and a tongue to prevent the escape of the filling from the hook until the shuttle pulls upon the filling as the shuttle moves to the opposite box.

9. In a loom, the combination of the lay 90 and shuttle boxes, a snarl preventer to engage within a loop of filling formed between the cloth and shuttle as the shuttle is picked, said snarl preventer being constructed and arranged to be disengaged 95 from said loop by the pull of the shuttle upon the filling as the shuttle traverses the lay.

In testimony whereof, I have signed my name to this specification, in the presence 100 of two subscribing witnesses.

ISAAC SNOW.
